(57) **CLAIM**

The ornamental design for a wrench, as shown and described.

DESCRIPTION

FIG. 1 is a perspective view of a wrench having an oval-shaped opening in its jaws;

FIG. 2 is a front view of the wrench of FIG. 1;

FIG. 3 is a left side view of the wrench of FIG. 1;

FIG. 4 is a top view of the wrench of FIG. 1; and,

FIG. 5 is a bottom view of the wrench of FIG. 1.

The broken lines depict portions of the wrench that form no part of the claimed design.
